United States Patent Office.

EDWIN J. TOOF, OF FORT MADISON, IOWA.

Letters Patent No. 78,158, dated May 19, 1868.

IMPROVEMENT IN PENCIL-HOLDERS.

The Schedule referred to in these Letters Patent and making part of the same.

TO ALL WHOM IT MAY CONCERN:

Be it known that I, EDWIN J. TOOF, of Fort Madison, in the county of Lee, and State of Iowa, have invented a new and improved Pencil-Holder; and I do hereby declare that the following is a full, clear, and exact description thereof, which will enable others skilled in the art to make and use the same, reference being had to the accompanying drawings, forming a part of this specification, in which—

Figure 1 is a perspective view of my improved holder, showing the manner of holding the same.

Figure 2 is a central longitudinal section of the holder.

Figure 3 is a detail view of the spring.

Similar letters of reference indicate corresponding parts.

The object of this invention is to provide a pencil-holder which bears an erasing-pad, suitably located on the exterior case of the holder, near the point of the pencil, whereby, in the operation of marking or writing, the erasing-pad will be presented in a convenient manner for expunging marks made by the pencil, as will hereinafter be duly set forth.

In the accompanying plate of drawings, the exterior case *b* holds the inner case *a*, the latter case sliding with easy contact within the case *b*, as shown.

The pad-socket *A* is affixed to or formed on the case *b*, as shown, and the pad *B*, which is, in practice, a piece of rubber or sponge, is compressed within the said socket, leaving a portion to project therefrom, as shown.

The pencil *e* is affixed in the case *a*, at the lower end of the latter; and the said case *b* has affixed thereto a finger-rest, *d*, as shown, for the purpose of pushing down the case *a*, and its contained pencil *e*, or retracting the same backward, so as to present the erasing-pad in a convenient and ready manner by merely flexing the index-finger, as will be obvious.

The cutter *c* is affixed to the end of the case *b* in any suitable manner, and serves to sharpen the pencil when necessary. The sharpening-operation is performed by withdrawing the case *a* entirely from the exterior case, and scraping the point of the pencil against the cutter in any manner most convenient for the person using the pencil.

The upper end of the case *a* is split, as shown at *f*, for the purpose of serving as a spring, to hold the case *a* from sliding too loosely within the exterior case.

The lower end of the case *b* is recessed, to permit the passage of the finger-rest *d* when the pencil is retracted.

This invention is designed more particularly for the employment of slate-pencils, but is equally applicable to lead-pencils.

A modification of my invention may be made by attaching the pad-socket *A* to the case in such a manner that it will slide in easy contact with the case, and be thereby retracted by the second finger. In this modification, the pencil *e* would remain stationary, and the socket, being mounted on a thimble sliding on the case, and provided with any suitable finger-rest, would be retracted when the pencil was to be used, and pushed downward when required for erasing, which is the reverse of the operation above shown and described, but otherwise substantially the same.

Having thus described my invention, I claim as new, and desire to secure by Letters Patent—

1. The combination of the case *b* and its erasing-pad *B* with the inner case *a* and finger-rest *d*, all constructed and operating substantially as shown and described, and for the purpose set forth.

2. The attachment of an erasing-pad, *B*, to the pencil-end of a pencil-case or holder, substantially as shown and described, and for the purpose set forth.

The above specification of my invention signed by me, this 4th day of March, 1868.

EDWIN J. TOOF.
